BLADE HOLDER.

Filed Nov. 26, 1928

UNITED STATES PATENT OFFICE

HENRY J. GAISMAN, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

BLADE HOLDER

Application filed November 26, 1928. Serial No. 321,794.

My invention relates to packages or containers for razor blades, and has for its object to provide means to retain a stack or pile of blades in position to be delivered, successively, to a portion of a safety razor when said portion is applied to the package.

In carrying out my invention I provide a container for the blades having one side open for insertion and removal of the blades, and movable means within the container to retain the blades, said means being operable by studs or projections carried by a blade member or backing of a safety razor when said studs are entered into the container and into openings in the blades therein, whereby to release the outermost blade for delivery to said backing, the said means, when released by said studs, being operative to retain the remainder of the blades within the container.

My invention also comprises details of improvement that will be more fully hereinafter set forth and then pointed out in the claims.

Reference is to be had to the accompanying drawings forming a part hereof, wherein

Fig. 1 is a plan view of my improved container, looking at the blade delivery side thereof;

Fig. 2 is a longitudinal section on line 2, 2 in Fig. 1;

Fig. 3 is a cross section on line 3, 3 in Fig. 1;

Fig. 4 is a section on line 4, 4, in Fig. 7, parts being broken away;

Fig. 5 is a perspective of a separator or spacer for the blades;

Fig. 6 is a view substantially similar to Fig. 2, showing a blade backing partly associated with the container;

Fig. 7 is a similar view showing the blade backing in blade-releasing position;

Fig. 8 is a perspective view illustrating a blade as delivered from the container to the blade backing;

Fig. 9 is a plan view of a modification;

Fig. 10 is a section on line 10, 10, in Fig. 9;

Fig. 11 is a section on line 11, 11, in Fig. 9;

Fig. 12 is a section on line 12, 12, in Fig. 13, parts being broken away;

Fig. 13 is a sectional view illustrating a blade backing applied to the container, and

Fig. 14 is a detail perspective of part of Figs. 9 to 13.

Similar numerals of reference indicate corresponding parts in the several views.

My improved package includes a container 1, shown in box-like form, having one side open at 2 for the admission and delivery of blades 3. The blades are arranged in a stack or pile within the container, and spacers 4 are shown interposed between the blades. In the form shown in Figs. 1 to 8 the spacers 4 are wider than the blades to successively engage inwardly extending webs 1a at the edges of the opening 2 of the container, to retain the stack of blades. The outermost spacer may be manually removed when a blade is to be delivered from the container, Fig. 3. The blades are shown provided with openings 3a, 3b, and the spacers are shown provided with openings 4a, 4b, which register with the openings 3a and 3b, respectively, when the blades and spacers are in a stack. The registering openings 3a, 4a, and 3b, 4b, are respectively adapted to receive studs or projections 5a, 5b extending from a blade backing or member 5 of a safety razor, the backing being shown in the form of a well known type of safety razor, (Figs. 6, 7, 8 and 13). Spaced guides 6 are shown adapted to enter registering openings 3a and 4a of the blades and spacers to guide the blades and keep their cutting edges out of contact with the container. Said guides may be pressed out of a metal plate 7 located within the container and against the back wall 1b thereof. Springs 8, which may be pressed out of plate 7, bear against the innermost blade of the stack to resiliently force the latter toward the opening 2 of the container. Blade retainers 9 pass through the registering openings 3a and 4a of the blades and spacers and are adapted to engage the outermost blade of the stack when the outermost spacer 4 has been removed. In the form shown in Figs. 1 to 7 the retainers 9 are resiliently supported by spring-like arms 10. Said arms may be pressed out of the plate 7, having a pivotal action at 10'. Portions 10a of the arms 10 extend from the retainers 9 in position to be engaged by the studs 5a of the backing 5. The retainers 9 are shown inclined relatively

to the blades, within the blade openings 3a, and said retainers are shown provided at their outer ends with stops 9' adapted to engage the adjacent edge of the associate blade opening 3a to normally retain the stack of blades when the outermost spacer 4 has been removed, (Fig. 6).

When the parts are in the position shown in Fig. 2 the outermost spacer 4 will be against the webs 1a of the container and the stops 9' will be against the outermost blade, so that the stack of blades will be retained within the container. When the outermost spacer 4 has been removed from the container the stops 9' of the guides 9 will engage the outermost blade and retain the stack of blades, as illustrated in Fig. 6. When the blade backing 5 is applied to the package its studs will pass through the openings in the blades and the spacers, (Fig. 6), and when the studs 5a engage the portions 10a of the arms 10 the latter will be moved inwardly, pivoting at 10', thereby withdrawing the stops 9' from the outermost blade of the stack to release the latter, whereupon said blade will drop upon the blade backing or member 5, and said stops will engage the next adjacent blade to retain the latter and the remaining blades until the backing 5 is removed from the container, (Fig. 7). When the backing has been removed the outermost spacer will engage the webs 1a of the container to retain the stack until a blade backing is again applied to the package or container. The operations will be performed for each of the blades successively.

In the form shown in Figs. 9 to 14 the retainers 9'', having the stops 9', are pivotally carried by the plate 7', and said retainers have two arms 9a and 9b, of different length, to alternately engage the blades. The retainers 9'' are shown provided with laterally extending pivots 11, (Fig. 14), located in bearings 12, which may be pressed out of the plate 7', adjacent to an opening 13 therein, in which opening the corresponding retainer 9'' swings. The arms 9a of the retainers 9'' are located within the openings in the blades and the spacers, and the arms 9b are outside of the blades, in the normal position of the parts, Fig. 10. Springs 14, which may be pressed out of plate 7', enter holes 16 in the arms 9a of the retainers 9'' and normally tend to tilt said retainers to the position shown in Fig. 10, so that the stops 9' of the arms 9b will engage the outer ends of the blades to retain the stack. The spacers are of less area than the blades, so that when a blade is released the adjacent spacer will drop away with said blade, Fig. 13. When a blade is to be removed the blade backing or member 5 will be applied to the package or container and the studs 5a will engage the arms 9a of the retainers 9'', thereby tilting said retainers so that the arms 9b will move away from

the outermost blade and the arms 9a will engage the next adjacent blade to retain the remaining blades and spacers, as illustrated in Fig. 13, the outermost blade and spacer dropping upon the backing. When the backing is removed from the package the springs 14 will tilt the retainers 9'' back to normal position, whereupon the arms 9b will pass under the outermost blade of the stack and the arms 9a will release the blades, whereby the stack of blades and spacers will descend to be retained by the stops 9' of the arms 9b, as from the positions shown in Fig. 13 to the positions shown in Fig. 10.

In accordance with my invention I provide a blade package in which the blades will be retained for removal, and in which it is merely necessary to apply a blade backing member of a safety razor to the package in order that the studs of the backing will actuate the outermost blade to cause the removal of the latter from the stack of blades and application of said blade to the backing. An advantage of my invention is that no manual handling of the blades is required to apply them to the blade backing 5, and no other operations are required to remove a blade other than to apply the blade backing to the package in the manner set forth. The spacers 4 sufficiently separate the blades of the stack to permit the ready entry between two blades of the stops 9', and while I have illustrated spacers in the form of sheets or plates, which may be of paper, other spacing means for the blades may be provided, such as a coating of paraffin on the blades.

My invention is not limited to the details of construction set forth, as the same may be varied, within the scope of the appended claims, without departing from the spirit of my invention.

Having now described my invention what I claim is:

1. A blade package comprising a container for blades provided with an opening for the passage of blades, and devices carried by the container to retain the blades therein, said devices being in position to be operated by studs from a razor member to release a blade.
2. A blade package as set forth in claim 1 in which the container is provided with means adjacent to said opening to retain spacers adjacent to the blade.
3. A blade package as set forth in claim 1 in which the container is provided with webs adjacent to said opening to retain spacers adjacent to the blades.
4. A blade package comprising a container for blades provided with an opening for the passage of blades, blades within the container, and devices carried by the container to retain the blades therein, said devices being operative in cooperation with the studs from a razor member to release a blade.

5. A blade package as set forth in claim 4 wherein means are provided to retain spacers adjacent to the blades.
6. A blade package comprising a container for blades provided with an opening for the passage of blades, a stack of blades, and spacers between the blades, the container being provided with means to retain blades, the container having means to engage an outermost spacer adjacent to the outermost blade to permit removal of the spacers and blades successively.
7. A blade package comprising a container for blades provided with an opening for the passage of blades, and blade retainers movably carried by the container in position to engage an outermost blade and to be operated in cooperation with studs from a razor member to release a blade.
- 20 8. A blade package as set forth in claim 7 provided with spring means to retain the retainers in cooperation with the blades.
9. A blade package as set forth in claim 7 provided with spring means to retain the retainers in cooperation with the blades, said spring means being in position to be operated in cooperation with studs from a razor member to actuate the retainers to release a blade.
- 30 10. A blade package comprising a container for blades, provided with an opening for the passage of blades, guides within the container for the blades to keep their cutting edges out of contact with the container, and retainers cooperative with the blades to retain the latter while they are guided by the guides, said retainers being in position to be operated in cooperation with studs from a razor member for actuating the retainers to release a blade.
- 35 11. A blade package comprising a container for blades provided with a side opening for the passage of blades, and movable retainers within the container operative with in openings in the blades to retain the latter within the container in register with the opening.
- 40 12. A blade package as set forth in claim 11 in which the retainers are movably carried in position to be operated by studs from a razor member to actuate the retainers to release a blade.
- 45 13. A blade package as set forth in claim 11 in which the container is provided with spring means operative with the blades to normally retain them in cooperation with the retainers.
- 50 14. A blade package as set forth in claim 11 provided with spring-like arms carrying the retainers, said arms having portions in position to be engaged by studs from a razor member to actuate the retainers to release a blade.
- 55 15. A blade package comprising a container provided with an opening for the passage of blades, webs adjacent to said opening to retain a spacer adjacent to a blade, spring means cooperative with the blades to retain them pressed toward the webs, and retainers movably carried by the container to enter openings in the blades to retain the latter.
- 60 16. A blade package as set forth in claim 15 in which the retainers are located in position to be engaged by studs from a razor member to operate the retainers to release a blade.
- 65 17. A blade package comprising a container for blades provided with an opening for the passage of blades, and retainers pivotally carried by the container to enter openings in the blades to engage and support the latter in register with the opening.
- 70 18. A blade package comprising a container for blades provided with an opening for the passage of blades, and retainers pivotally carried by the container, said retainers having arms, one arm being arranged to engage the blades to retain them normally within the container and the other arm being arranged to enter openings in the blades to retain blades when the first named arm releases an outermost blade.
- 75 19. A blade package as set forth in claim 18 in which the second named arms are in position to be actuated by studs from a razor member when said studs are entered into the openings in the blades.
